(57) CLAIM

The ornamental design for an illuminated removable cover for trailer hitch, as shown and described.

DESCRIPTION

FIG. 1 is a perspective view of the illuminated removable cover for trailer hitch embodying the design of the present invention, shown in exploded condition;

FIG. 2 is a front elevational view shown with the cover attached;

FIG. 3 is a rear elevational view of FIG. 2;

FIG. 4 is a left side elevational view of FIG. 2;

FIG. 5 is a right side elevational view of FIG. 2;

FIG. 6 is a top plan view of FIG. 2;

FIG. 7 is a bottom plan view of FIG. 2; and,

FIG. 8 is a reduced perspective view showing the illuminated removable cover for trailer hitch in use.

The broken line showing of environmental structure is for illustrative purposes only and forms no part of the claimed design.
